STORM SASH

Bernard E. Mendelsohn, Newton, Mass.
(5-7 Livingstone St., Dorchester, Mass.)
Filed Jan. 23, 1961, Ser. No. 84,416
8 Claims. (Cl. 20—55)

This invention relates to storm windows and more particularly comprises an improvement upon the storm window sash disclosed in my co-pending application Serial No. 20,770, filed April 7, 1960, and entitled Storm Window. This application is a continuation-in-part of that earlier application.

In my earlier application, *supra*, I disclosed a multi-sash tilt-type storm window wherein each of the several sashes carries extendable flanges in the side members, which when extended lie within channels formed in the window frame. The flanges carried on the side members of the sashes extend substantially throughout the full height of the sashes and are moved by means of actuators attached to the extreme ends of the flanges. The actuators disposed at the top of the sashes and secured to the upper ends of the flanges are friction loaded so that the upper parts of the flanges remain in the position chosen by the operator. However, the actuators at the bottoms of the sashes secured to the lower ends of the flanges are spring loaded to urge the flanges outwardly beyond the sides of the sashes and into the channels of the window frame.

The features of the earlier invention outlined above are all incorporated into the sash of the present invention. However, the storm sash of the present invention includes additional features which aid in its assembly and generally enhance the strength of the sash.

My invention will be better understood and appreciated from the following detailed description of the preferred embodiment thereof, read in connection with the accompanying drawings in which:

FIGURE 1 is a fragmentary front elevation view of a sash constructed in accordance with my invention;

FIGURE 2 is a fragmentary side elevation of the sash shown in FIGURE 1;

FIGURE 3 is an enlarged fragmentary perspective view, partly in section, showing a portion of the sash of FIGURE 1;

FIGURE 4 is a cross-sectional elevation view of a portion of the sash shown in FIGURE 1;

FIGURE 5 is a view similar to FIGURE 4 but showing an alternate position for part of the mechanism;

FIGURE 6 is a cross-sectional view taken along the corresponding section line in FIGURE 3;

FIGURE 7 is an exploded elevation view of a portion of the sash shown in FIGURE 1; and

FIGURE 8 is a cross-sectional view taken along the corresponding section line in FIGURE 7.

The embodiment of the storm sash shown in the drawings includes in its general organization a sash frame 10 having a side member 12, a top member 14, a bottom member 16 and glass 18. It will be appreciated that a second side member identical to side member 12 shown in FIGURE 1 extends parallel to the side member 12 on the other side of the sash.

The side member 12 is generally H-shaped in cross-section as shown in FIGURE 6 and includes generally parallel sides 20 and 22 interconnected by a web or cross member 24. This H-shaped cross-sectional configuration defines a pair of channels 26 and 28 disposed back to back and opening in opposite directions. The channels are generally vertically oriented and extend from the top member 14 to the bottom member 16. A secondary channel 30 is formed within the general confines of the channel 28 and is defined by sides 32 and 34 and panel

2

36. The secondary channel 30 extends throughout the full length of the side member 12 and contains a length of weather stripping as suggested at 38. The weather stripping 38 is so positioned that it bears against the supporting or bearing surface on the storm window frame (not shown) when the sash is mounted in the frame. This feature of my invention is disclosed in detail in my co-pending application Serial No. 20,770, *supra*, and does not form part of this invention.

The top member 14 and the bottom member 16 join the top and bottom of the side member 12 at mitered corners as suggested at 40 and 42 in FIGURE 1. The bottom member 16 and the top member 14 are virtually identical to the similar members of the sash shown in my earlier co-pending application, *supra*. The top and bottom members each include a channel identified respectively by numerals 44 and 46, that form continuations of the channel 28 of the side member 12 when the three parts are assembled together. The channels 44 and 46 open inwardly of the sash 10, that is, face the inside of the dwelling upon which the storm window is mounted.

Corner brackets 48 and 50 are employed to join the top member 14 with the side member 12 and the bottom member 16 with the side member 12, respectively. The corner bracket 50 is shown in cross-section in FIGURES 4 to 6 and is shown partly broken away in FIGURE 3. The bracket 50 includes a horizontal arm 52 disposed in the channel 46 of the bottom member 16 and a vertical arm 54 disposed in the channel 28 of the side member 12.

30 The horizontal arm 52 is composed of a face plate 56 and a pair of horizontally disposed and spaced apart flanges 58 and 60 which bear against the sides of the channel 46 in the bottom member 16. The face plate 56, the flanges 58 and 60, and the base of the channel 46 cooperate to define an enclosed track within which is mounted a latch 62 described in detail below. The vertical arm 54 of the bracket 50 includes a face plate 64 which bears against the inner surface of the side 22 of the side member 12 and a flange 66 disposed against the base of the channel 28 as defined by the web 24. It will be noted particularly in FIGURE 6 that the flange 66 and the plate 64 fit snugly within the channel 28. In FIGURES 3 and 6 it will also be noted that a lip 68 is formed as an integral part of the side 22 of side member 12 and is provided with an undercut inner surface 70 that engages a mating surface 72 formed on the end of the face plate 64 of the vertical arm 54. The undercut surface 70 of the lip 68 cooperates with the general character of the fit of the vertical arm 54 in the channel 28 to hold the vertical arm firmly in place. It also provides specific resistance against displacement of the vertical arm 54 in the channel 28 when the vertical arm is staked in place as suggested at 74.

45 The horizontal and vertical arms 52 and 54 of the bracket 50 are approximately one inch in length and it is essential that in the relatively short distance provided a firm connection be made between the bracket arms and the bottom and side members of the sash. It is to be noted that the corner bracket 48 which serves to interconnect the top member 14 and the side member 12 is virtually identical to the corner bracket 50 and specifically is provided with a tapered surface at the end of the face plate to cooperate with the undercut surface 70 provided on the lip 68 which extends the full length of the side member 12.

55 A retractable flange 80 is floated within the channel 28 of the side member 12 and cooperates with a channel or track formed in the window frame (not shown) to enhance the weather tightness of the storm window. As I described in detail in my earlier co-pending application, *supra*, the retractable nature of the flange 80 permits the sash to be assembled readily as a tilt-type window within the frame but yet provides the full protection of

the track-type windows of the prior art. That is, because the flange 80 may be withdrawn wholly within the confines of the channel 28 in the side member 12, the sash may be tilted inwardly when the flange is so withdrawn, to facilitate cleaning and removal, but when the sash is mounted in the frame and the flange extends into the track or channel of the frame it forms a weather-tight seal along the sides of the sash. In FIG. 6 flange 80 is shown spaced from members 36 and 64. In actuality flange 80 has a tighter fit with these members than actually shown.

The flange 80 extends substantially coextensive with the side member 12 to provide the benefits of a tight connection with the frame through substantially the full height of the sash. The flange includes a main plate or panel 82 oriented parallel to the sides 20 and 22 of the side member 12 and a rib 84 forming a continuation of the panel 82 at its inner edge and disposed parallel with the web 24 of the side member. It will be noted in FIGURE 7 that the rib 84 is not coextensive with the panel 82 but rather terminates short of its ends as suggested at 86 and 88. The inner edge of the panel 82 represented by line 89 in FIGURES 7 and 8 terminates a short distance from the web 24 of the side member 12 to form a gap between the panel and web. The rib 84 throughout the major portion of the flange 80 fills that gap so that the rib 84 actually contacts the web 24 when the flange is withdrawn within the channel 28. To facilitate complete withdrawal of the flange 80 into the channel 28 it is necessary to eliminate from the ends of the flange 80 the rib 84 as the plate 66 of the vertical arm 54 of the bracket 50 is disposed in the area which would otherwise be occupied by the end of the rib 84. Thus, the rib 84 is in effect cut away at the ends of the flange to provide room for the portion of each corner bracket which lies against the web 24 at the ends of the side member 12.

Earlier I referred to latch 62 slidable within the enclosed track defined by the horizontal arm 52 of bracket 50 and the base of channel 46 in the bottom member 16. The latch 62 includes an enlarged head 90 which rides along the side of the window frame in which the sash is mounted and may cooperate with stops formed on the inside of the frame to retain the sash in an open position. It will be noted that the latch carries an upwardly extending tongue 92 just rearwardly or inwardly of the head 90, that engages a slot 94 cut in the bottom of the panel 82 of the flange 80 to support the flange in the channel 28 of the side member 12. The tongue 92 has an enlarged base in the form of a shoulder 96 that serves to space the tongue 92 from the plate 66 of the vertical arm 54 of the bracket 50. Thus, as is shown in FIGURE 4, the tongue 92 is spaced from the plate 66 a distance which is adequate to receive the tine 98 forming one side of the slot 94 in flange 80. A similar arrangement is used to support the upper end of the flange 80. It will be noted in FIGURE 7 that a slot 100 is provided at the upper end of the plate 82 of the flange 80 to receive a tongue carried by the latch 102 disposed in the track formed by the horizontal arm of the bracket 48 and the base of the channel 44 in the top member 14.

The shoulder 96 serves as a guide or gauge to facilitate the assembly of the sash frame. When the bottom member 16 is secured to the side member 12 by means of the bracket 50 and the latch 62 is disposed in the position shown in FIGURES 3 and 4, the shoulder 96 spaces the tongue 92 from the inner surface of the plate 66 of the vertical arm of the bracket and the flange 80 may be slipped into the channel 28 formed in the side member. By running the flange 80 against the web 24 the tine 98 falls in place behind the tongue 92. Thus, what otherwise could be a problem in assembling the window is avoided. Similarly, when the top member 14 is connected to the side member 12 the tongue on the latch 102 will automatically align itself with the slot 100 at the top of the flange and slip into place.

The configuration of the flange 80, namely, the presence of the rib 84 normal to the panel 82 which makes up the major portion of the body of the flange provides a guide to prevent the floating flange from distorting or wobbling. The rib 84 bears against the inner surface of the side 22 of the side member while the ends of the panel 82 ride on the face plates of the vertical arms of the top and bottom brackets 48 and 50. Throughout the length of the flange 80, the panel 82 is also guided between the lip 68 formed on the outer end of the side 22 and the inner face of the panel 36 which defines in part the secondary channel 30. The rib 84 formed as a bend in the panel 82 also adds a great deal of stiffness to the flange to prevent twisting.

From the foregoing description it will be appreciated that numerous modifications may be made of my invention without departing from its spirit. Therefore, I do not intend to limit the breadth of my invention to the single embodiment illustrated and described. Rather, it is my intention that the scope of this invention be determined by the appended claims and their equivalents.

What is claimed is:

1. In a storm window, a sash having a side member, a bottom member and a connecting bracket; said side member having a generally H-shaped cross-section with inner and outer parallel sides and a connecting web defining back to back inner and outer channels, said bottom member having a U-shaped cross-section open inwardly of the sash to define a channel, said connecting bracket being generally L-shaped and having a horizontal arm lying in the channel of the bottom member and a vertical arm lying in the outer channel of the side member, a plate forming part of the vertical arm of the connecting bracket and extending between and engaging the inner and outer parallel sides and the web of the side member, a second plate forming part of the vertical arm of the connecting bracket and disposed parallel to and lying against the inner side of the side member, a lip formed on the free end of the inner side of the side member and having an undercut surface engaging the outer end of the second plate, an extendable flange lying in the outer channel of the side member and disposed parallel to the inner and outer sides of the side member, a rib forming part of the flange and extending along its inner edge parallel with the web and terminating at the lower end of the vertical arm of the connecting member, a movable latch disposed in the channel of the bottom member and retained in the channel by the horizontal arm of the connecting bracket, a tongue extending upwardly from the latch into the outer channel of the side member, a shoulder formed on the latch and spacing the tongue from the web of the side member, and a slot formed in the bottom of the flange and engaged by the tongue of the latch.

2. In a storm window, a sash having a side member, a bottom member and a connecting bracket; said side member having an outwardly opening channel, said bottom member having an inwardly opening channel, said connecting bracket having a horizontal arm lying in the channel of the bottom member and a vertical arm lying in the bottom portion of the channel of the side member, a plate forming part of the vertical arm of the bracket and extending across the channel of the side member at the base of the channel and a second plate lying against one side of the channel, a retractable flange disposed in the channel of the side member and extending downwardly below the top of the vertical arm of the bracket, a rib formed as part of the flange and disposed parallel to the base of the channel of the side member and terminating at the bottom above the top of the vertical arm of the bracket, a vertically extending slot in the lower end of the flange and spaced from the inner edge of the flange a selected distance, a latch disposed in the channel of the bottom member and retained by the horizontal arm and adapted to retain the sash in the frame, a tongue secured

to the latch and disposed in the slot of the flange, and a shoulder formed on the latch at the base of the tongue spacing the tongue said selected distance from the base of the channel of the side member.

3. A storm window comprising a sash, said sash having bottom member, a side member and a connecting bracket secured to the bottom and side members, a channel formed in the side member and open outwardly away from the sash, a flange disposed in the channel and free to move in and out of the channel, a latch forming part of the bracket and movable in the channel of the bottom member, a tongue secured to and forming part of the latch and extending into the channel of the side member, a slot in the bottom of the flange receiving the tongue of the latch, and a shoulder formed in the latch at the base of the tongue and spacing the tongue a distance from the base of the channel in the side member to enable the margin of the slot in the flange to lie between the base of the channel and the tongue.

4. A storm window sash comprising a side member, a bottom member, a connecting bracket joining the ends of the side and bottom members, a channel formed in the outer side of the side member, a movable latch disposed in the bracket and having a tongue extending upwardly in the channel of the side member, a shoulder formed as part of the latch and spacing the tongue a selected distance from the base of the channel when the latch is in a retracted position, a flange disposed in the channel of the side member and movable in and out of the channel, means defining spaced tines at the bottom of the flange engaging the inner and outer sides of the tongue, the inner of said tines being smaller than the selected distance as determined by the shoulder to fit on the inner side of the tongue when the latch is in a retracted position.

5. In a storm sash, a side member, means defining a channel in the side member opening outwardly to the side of the sash, a flange movable in and out of the channel and extending substantially the full length of the side member, parallel top and bottom members, connecting means including a tongue connecting the top and side members together and supporting the upper end of the flange in the channel of the side members, second connecting means including a tongue connecting the bottom and side members together and supporting the bottom of the flange in the channel, and spacers secured to each of the connecting means spacing the tongues from the base of the channel in the side member so that a portion of the

flange may be disposed inwardly of the tongue in the channel.

6. In a storm sash, a side member, a channel in the side member opening outwardly to the side of the sash, said channel defining a pair of parallel sides and a cross web in the side member, a flange movable in and out of the channel including a plate extending substantially the full length of the side member and lying parallel to the sides of the channel and disposed adjacent one of the sides in the channel, a rib forming part of the flange and secured to the inner edge of the plate and disposed parallel to the web, one edge of the rib disposed adjacent the other of the sides of the channel to guide the movement of the flange in the channel and to stiffen the flange, and actuating means attached to the side member and the flange for moving said flange in and out of the channel.

7. In a window sash, a side member, a bottom member, a first connecting bracket securing together said side and bottom members, a top member, a second connecting bracket securing together said top and said members, a channel formed in the side member and opening outwardly to the side of the sash, a vertically oriented flange including a plate disposed in the channel and movable in and out of the channel, actuating means attached to at least one bracket and the flange for moving said flange in and out of the channel, said first connecting bracket having a vertical arm disposed in the channel which extends upwardly above the bottom of the plate and said second bracket having a vertical arm disposed in the channel which extends downwardly below the top of the plate, and a rib forming part of the flange and secured to the rear edge of the plate and terminating at its lower end above the vertical arm of the first bracket and terminating at its upper end below the vertical arm of the second bracket, said rib providing stiffness to the flange and guiding the flange in its movement in and out of the channel.

8. A sash as defined in claim 7 further characterized by said channel having parallel side walls and a base wall, the plate of said flange disposed parallel to sides of the channel and lying against one of the sides of the channel, and said rib being disposed normal to the plate and engaging the other of the sides of the channel.
